UNITED STATES PATENT OFFICE.

JAMES R. FLEMING, OF SCRANTON, PENNSYLVANIA.

JOURNAL BOX FOR CAR WHEELS.

Application filed September 10, 1926. Serial No. 134,626.

My invention relates to journal boxes for car wheels and more particularly to journal boxes adapted for the support of roller bearings and which may be readily removed 5 from the axle when desired.

Heretofore, journal boxes have been constructed in two parts consisting of a top plate and a barrel within which a roller bearing is supported. The top plate is adapted 10 to be secured to a car sill and to act as a hanger for the support of the barrel. The barrel and top plate are so constructed that the barrel may be slid into engagement with the top plate and is retained between an 15 abutment formed on the top plate and the car wheel.

Journal boxes of the type referred to and to which my invention pertains are adaptable to both fixed and loose wheels and may 20 be removed from the axle. However, such boxes are open to a number of objections, chief among which is that while such boxes are removable they are not, under all circumstances, readily removable and as constructed 25 require for their removal displacement of the top plate or hanger in all circumstances.

Now, it is the object of my invention to provide a journal box of the type indicated, which will possess all the advantages of such 30 boxes as heretofore constructed and in addition thereto will be readily removable from the axle in all circumstances and without displacement of the top plate or hanger from which it is supported.

Having now indicated, in a general way, the nature and purpose of my invention, I will proceed to a detailed description thereof with reference to the accompanying drawings in which there are shown preferred em- 35 bodiments of my invention and in which:—

Fig. 1 is a plan view, partly broken away, of a journal box embodying my invention.

Fig. 2 is an end view of the subject of Figure 1.

Fig. 3 is a sectional view on line 3—3 Figure 2.

Fig. 4 is sectional view on line 4—4 Figure 2.

Fig. 5 is an end view of a journal box 50 embodying a modification of my invention.

Fig. 6 is an inverted plan view of the subject of Figure 5.

Referring more particularly to Figures 1—4, in which there is illustrated a journal 55 box assembly involving my invention, *a* indicates the base portion of a top plate, or

hanger, adapted to be secured to a car sill *b*. The base portion of the top plate is provided with bosses *c*, which are adapted to enter recesses in the sill and aid in aligning 60 the plate. The plate may be secured to the sill by means of bolts passed through holes drilled through the bosses *c*. The base portion of the top plate is made of such width as to have a portion extending beyond the 65 outer face of the sill, as is clearly shown in Figure 1.

The top plate, or hanger, is provided, beneath the base portion, with downwardly and inwardly extending flanges, which form 70 slideways. The portion of the base which extends beyond the outer face of the sill is drilled, at points above the end portions of the slideways formed by the flanges *d*, for the passage of bolts *e*, which act to block 75 the ends of the slideways and the end portions of which protrude through suitable holes drilled in the inturned portions of the flanges *d*. The bolts may be held in place by means of cotter pins *f*.

The barrel, or journal box *g* is formed, in the embodiment illustrated, to receive a roller bearing, which is entered in the barrel and retained therein against an internal web *i*, by means of an end cap *j* secured to a 85 flange *k* at one end of the barrel, by means of rivets *l*. The end of the barrel opposite to that closed by cap *j* is permanently closed by an end wall *m* provided with an oil hole *n*, which forms an oil reservoir with the 90 internal web *i*. The web *i* and end cap *j* are provided with openings for the passage of the end portion of an axle *o* upon which is mounted a wheel *p*.

The barrel, or box, is provided on its top with a rounded pad *h* and adjacent its top with oppositely extending flanges *q* adapted to enter the slideways formed by flanges *d* depending from the base portion of the top plate or hanger.

In practice assuming the top plate, or hanger, to be secured to a car sill, as indicated in Figure 1, and the bolts *e* removed, the car is supported, as by a jack, at the proper height and the axle *o* is positioned 105 beneath the hanger. The box *g* is then slid on the end of the axle until the flanges *q* are within the slideways in the hanger. The bolts *e* are then put in place. As will be now observed, after the bolts are put in 110 place, the box cannot be withdrawn from the hanger and it will be prevented from passing

through the hanger by the wheel p , against the hub of which the end of the box will contact before the flanges q can leave the slideways.

5 The slideways are so proportioned and the pins e so positioned with reference to the wheel p that the box will have substantial movement on pad h , which will bear beneath the base portion a , in order to permit automatic alignment of the bearing.

10 Referring now more particularly to Figures 5 and 6, in which there is illustrated a modified embodiment of my invention, a' indicates the base portion of a top plate 15 or hanger, provided with bosses c' and adapted to be secured beneath a car sill, by means of bolts passing through suitable holes drilled in the base portion and bosses.

15 Beneath the top plate depends a flange r , which forms a quadrilateral recess, closed adjacent one end as shown at s , Figures 5 and 6. Adjacent the other end of the recess the flange r is drilled for the passage of a bolt t , which may be retained by means 20 of a cotter pin f' .

25 The barrel or journal box u , having a rounded pad h' on its top, is preferably cylindrical and adapted for the reception of a roller bearing within which the end portion of an axle o' , upon which is mounted a wheel p' , is adapted to extend. The box u has formed on it laterally extending wings or flanges v , one of which is adapted to be extended within the closed end of the 30 recess formed by the flange r and the other of which is adapted to be retained within the recess by means of bolt t .

35 In practice, assuming the hanger or top plate to be secured to the car sill, the bar-

rel or journal box is slipped on the end portion of the axle o' and tipped to enter one of the wings or flanges v within the closed end of the recess formed by flange r . The other wing or flange v is brought into the recess and the bolt t put in place. As will 40 be noted, the bolt t passes beneath the wing v and acts to retain the box in engagement with the hanger; further the box is capable of substantial movement about pad h' permitting automatic alignment of the bearing. 45 50

Having now fully described my invention, what I claim and desire to protect by Letters Patent is:—

55 A journal box for car wheels comprising a hanger adapted to be secured to a car and a barrel carrying a bearing for the end of an axle, said barrel being provided with oppositely extending flanges and said hanger having guideways formed therein to receive said flanges, said guideways extending parallel to the axle and open at their outer ends to permit removal of the barrel by axial outward movement thereof relative to the hanger, and removable pins extending across said guideways and engaging the flanges to normally prevent outward movement of the barrel, said guideways being higher than said flanges to permit relative vertical movement between the barrel and hanger, and a stop means for limiting vertical movement between the hanger and bearing comprising a member on one engaging a surface on the other. 60 65 70

75 In testimony of which invention, I have hereunto set my hand, at Scranton, Pennsylvania, on this fourteenth day of August, 1926.

JAMES R. FLEMING.
